Bert K. Naster, Hollywood, Fla.

Application November 21, 1957, Serial No. 698,012

7 Claims. (Cl. 323—45)

This invention relates to a voltage regulator, adapted to supply substantially constant output voltage over a wide range of input voltage.

One object of the present invention is to provide a new and improved voltage regulator utilizing electro-magnetic elements and maintaining a high degree of regulation over a wide range of input voltages.

A further object is to provide a new and improved voltage regulator of the foregoing type which achieves a degree of regulation far exceeding that achieved with prior magnetic regulators, and comparing very well with the regulation achieved with the best electronic regulators.

Another object is to provide a voltage regulator which is extremely rugged and compact, yet is reasonably easy to manufacture and low in cost.

Further objects and advantages of the present invention will appear from the following description, taken with the accompanying drawing, in which:

Fig. 1 is a schematic wiring diagram of a voltage regulator to be described as an illustrative embodiment of the present invention.

Fig. 2 is a somewhat pictorial wiring diagram of the regulator, showing the general layout of the magnetic cores and coils.

Fig. 3 is a somewhat simplified circuit diagram of the regulator.

Fig. 4 is a plan view of one of the transformers employed in the regulator.

Fig. 5 is a cross-sectional view, taken generally along the line 5—5 in Fig. 4.

Figs. 6—13 are vector diagrams illustrating the operation of the regulator.

As already indicated, Figs. 1—3 illustrate a regulator 10 adapted to furnish a substantially constant output voltage at a pair of output terminals 12 and 14, even though the input voltage supplied to the regulator may vary over a considerable range. The input voltage is applied to a pair of input terminals 16 and 18. In the arrangement of Figs. 1 and 2, the input terminals 16 and 18 take the form of the prongs of a plug 20, adapted to be inserted into an ordinary household electrical receptacle. Similarly the output terminals 12 and 14 are formed on a receptacle 22, into which an appliance or the like may be plugged.

The input will often be alternating current from an ordinary household power line supplying approximately 115 volts at 50 cycles. However, the regulator may be made to operate at any desired input voltage and frequency. The regulator will often be arranged to supply a regulated output voltage of 115 volts, but it may be made to supply any desired output voltage.

The regulator has many applications. Thus, it may be employed to supply a closely regulated voltage to military, industrial or laboratory devices. In the home, the regulator may be employed to supply a regulated voltage to a television receiver or any other appliance for which a regulated input is desirable.

From Figs. 1 and 2, it will be apparent that the reg-

2

ulator 10 comprises first and second transformers 24 and 26. As illustrated to best advantage in Figs. 2 and 4, the first transformer 24 has a magnetic core 28, which may be made up of a stack of iron laminations, in the usual manner. The core 28 may be arranged in various ways, but the illustrated core is provided with an elongated central leg 30 which extends longitudinally across an elongated rectangular ring 32. Saturable butt joints 34 and 36 are provided between the central leg 30 and the ring 32 at the opposite ends of the central leg.

The first transformer 24 has a first primary coil P1 which is mounted on the central leg 30 adjacent one end thereof. In addition, the first transformer 24 has first, second and third secondary coils S1, S2, and S3, all of which are mounted on the central leg 30. It will be seen that the first secondary coil S1 is mounted at the extreme right-hand end of the central leg 30, immediately adjacent the primary coil P1. The second and third secondary coils S2 and S3 are on the opposite end of the primary coil, with the second coil S2 disposed between the primary coil P1 and the third coil S3.

In order to give the second secondary coil S2 a high degree of leakage reactance, magnetic shunts 38 are provided on the core 28 between the primary coil P1 and the secondary coil S2. In this case, the shunts 38 take the form of projections which extend inwardly from the ring 32 into closely spaced relation to the central leg 30.

Similarly, magnetic shunts 40 are interposed between the second and third secondary coils S2 and S3, to give the third coil S3 an extremely high degree of leakage reactance. It will be realized that both the shunts 38 and 40 are between the primary coil P1 and the third secondary coil S3. The shunts 40 are somewhat wider than the shunts 38 and, thus, have a greater magnetic shunting effect.

From Fig. 2, it will be apparent that the second transformer has a magnetic core 42 which is somewhat similar to the core of the first transformer 24. Thus, the core 42 has an elongated central leg 44 which extends across an elongated rectangular ring 46. Saturable joints 48 and 50 are provided between the leg 44 and the ring 46 at the opposite ends of the central leg 44.

The second transformer 26 has a second primary coil P2 and a fourth secondary coil S4, both of which are mounted on the central leg 44 at the opposite ends thereof. Magnetic shunts 52 are interposed between the secondary coil S4 and the primary coil P2, to give the secondary coil a high degree of leakage reactance.

The circuit arrangement of the primary and secondary coils is subject to numerous variations. In the illustrated arrangement, however, the first and second primary coils P1 and P2 of the first and second transformers 24 and 26 are connected in series between the input terminals 16 and 18. The input circuit between the terminals 16 and 18 may be traced along a lead 54, the first primary coil P1, a lead 56, the second primary coil P2, and a lead 58. The secondary S4 on the second transformer 26 is arranged to feed power into the primary P1 on the first transformer 24. In this case, the secondary S4 is connected directly across the first primary coil P1.

In the illustrated arrangement, the second output terminal 14 is connected directly to the second input terminal 18, by means of a lead 60 which is connected to the lead 58. The first input terminal 16 is connected to the first output terminal 12 by a series circuit that may be traced through the lead 54, the first primary coil P1, the first secondary coil S1, a lead 62, the third secondary coil S3, and a lead 64. It will be observed that the first secondary coil S1 is connected to the junction between the first and second primary coils P1 and P2.

The regulator 10 is provided with a capacitive feed back circuit, which comprises a capacitor C1. In this case,

the capacitive feed back circuit is connected between the junction lead 62 and the first input terminal 16. The feed back circuit comprises the second secondary coil S2 and the capacitor C1 in series. It will be noted that the capacitive feed back circuit is connected to the junction between the secondary coils S1 and S3. The current in the feed back circuit results from the voltages across the first primary coil P1 and the first secondary coil S1, as well as the voltage across the second secondary coil S2. The output current through the third secondary S3 also has an effect on the current through the feed back capacitor C1.

To improve the regulation and the waveform of the output voltage a second capacitor C2 is connected across the terminals 12 and 14.

Various other refinements of the circuit are shown in Figs. 1 and 2. Thus, a fuse 66 and a switch 68 may be connected in series with the lead 54. A pilot lamp 70 may be mounted across the input leads 54 and 58. In this case, the lamp 70 is of the neon type, with a current limiting resistor 72 in series therewith. A voltmeter 74 may also be connected between the leads 54 and 58, to indicate the input voltage. Similarly, a second voltmeter 76 may be connected between the output terminals 12 and 14 to indicate the output voltage.

In the arrangement of Fig. 1, the primary coils P1 and P2 and the secondary coils S1 and S4 are provided with tap switches 78, 80, 82, and 84 to adjust the output voltage and compensate for variations in the output load. These tap switches constitute a refinement which is not strictly necessary, particularly when the output load is constant and the desired output voltage is known. It will be seen that the tap switch 78 is adapted to switch the lead 56 to any of various taps 88 at the end of the first primary coil P1, so as to make slight changes in the number of turns in the coil P1 which are across the secondary S4.

The tap switch 80 is adapted to switch the input lead 58 between any of a plurality of taps 90 at the end of the secondary primary coil P2. In this way, the effective number of turns in the coil P2 is changed slightly.

The tap switch 82 is similarly adapted to switch the lead 62 to any of a plurality of taps 92 at one end of the first secondary coil S1. This changes the effective number of turns in the coil S1.

In like manner, the tap switch 84 is connected to various taps 94 at one end of the coil S4, so as to change the effective number of turns in the coil.

In Fig. 2, arrows have been drawn on the various coils to indicate the direction of winding. While the construction of the coils may be varied to a considerable extent, it may be helpful to present detailed information with respect to one actual model which has been employed with a high degree of success. This information may best be presented in tabular form. Thus, the following table shows the number of turns, the operating voltage, and the current in each coil, as recorded in an actual test, in which the model was connected to a resistive load drawing 100 watts, at a regulated output voltage of about 112 volts, and an input voltage of about 118 volts:

Coil	Number of turns	Operating Voltage	Current (Amp.)
P1	450	85	2.74
S1	197	68	.84
S2	1035	410	1.61
S3	1035	115	.805
P2	750	83.5	1.1
S4	765	85	.80
C1		555	1.61

It was observed that the voltages across S4 and P2 were about 110 degrees out of phase with each other. The voltages across P1 and S1 were 180 degrees out of phase.

For this test, the value of the first capacitor C1 was 7

microfarads, while the value of the second capacitor C2 was 4.75 microfarads.

It has been found that the regulator maintains nearly constant output voltage over an extremely wide range of input voltage. The performance of the regulator is outstanding; not only with respect to the degree of regulation achieved, but also with regard to the extremely wide range of input voltage that may be accommodated. The excellent regulation achieved by the regulator is demonstrated by the following table, which shows the results of an actual test in which the output voltage was observed as the input voltage was varied over a wide range.

Input voltage	Regulated output voltage
95	104
100	108
110	111
120	113
130	114
140	114
150	113
160	112
170	110
180	108
190	105
200	103

It is somewhat difficult to give a concise explanation as to how the regulator operates to provide a substantially constant output voltage as the input voltage is varied. However, the regulation is believed to be due to several factors. One factor is the manner in which the second transformer 26 feeds power back into the first transformer 24, by way of the secondary S4. Another factor is thought to be the manner in which the first capacitor feeds leading current back to the input terminal from the coils P1, S1, and S2. Still another factor is the high leakage reactance of the secondary coils S2, S3, and S4. Moreover, there is also the variable reluctance provided by the saturable joints 34, 36, 48 and 50 at the ends of the central legs on the transformers.

It is believed that a condition of resonance or near resonance exists in the capacitive feed back circuit. This is evident from the high voltages across the capacitor C1 and the secondary S2. These high voltages indicate that the capacitive reactance of the capacitor and the inductive reactance of the coil S2 are largely cancelling each other so as to permit the flow of a relatively large current through the feedback capacitor.

The resonance condition in the capacitor circuit is illustrated in the vector diagrams of Figs. 6-13. These diagrams are based in part on the fact that the output voltage is the vector sum of the input voltage plus the voltages across C1, S2, and S3. Figs. 9-13 illustrate this vector addition for several different values of input voltage. In these diagrams, the input voltage is designated V_{IN} while the output voltage is designated V_{OUT} . The voltages across C1, S2, and S3 are designated V_{C1} , V_{S2} , and V_{S3} .

It will be seen from Figs. 9-13 that the vector representing the sum of the voltages across C1, S2, and S3 increases with increasing input voltage. Actually, this vector increases somewhat more rapidly than the increasing voltage. The vector rotates in angular position as the input voltage is increased, so as to maintain the output voltage substantially constant.

The vector diagrams of Figs. 6, 7, and 8 are drawn to account for the rotation and rapid increase of the vector representing the sum of the voltages across C1, S2, and S3. These diagrams are based on the observation that the last mentioned vector is the sum of the vectors representing the voltage across C1 and the sum of the voltages across S2 and S3. The diagrams of Figs. 6, 7, and 8 are for successively increasing input voltages of 100, 120 and 140 volts. It will be observed that both the vector V_{C1}

and the vector V_{S2} plus V_{S3} increase with increasing input voltage, but the increase of V_{C1} is somewhat more rapid, with the result that the vector V_{C1} plus V_{S2} plus V_{S3} rotates in angular position and increases rapidly in value.

It will be realized that the present voltage regulator represents an outstanding achievement, in that the regulator provides a degree of regulation much greater than for prior magnetic regulators. The degree of regulation compares very well with the best electronic regulators. It has been found that the regulating action is very rapid, with the result that the output voltage is completely stabilized within two or three cycles of the alternating current, after any change in the input voltage.

The regulator is of great value for use with military, industrial and laboratory equipment requiring constant input voltage. It is also advantageous for use with a television set, to prevent variations in line voltage from affecting the picture. When the regulator is thus employed, the line voltage may change a great amount without any perceptible change or unsteadiness in the picture.

The regulator has another surprising and highly advantageous feature, in that the output terminals may be short circuited without damaging the regulator or causing excessive current in the input or the output circuit. It is thought that this result may be attributed to the high leakage reactance of the secondary S3. Because of this feature, the regulator is immune to damage due to accidental short circuits across the output terminals. Moreover, the regulator restores the output voltage as soon as the short circuit is removed.

Since the regulator employs magnetic components, it is extremely durable and compact, yet is reasonably low in cost. There are no moving parts or electric components to get out of order.

Various modifications, alternative constructions and equivalents may be employed without departing from the true spirit and scope of the invention, as exemplified in the foregoing description, and defined in the following claims.
